(57) **CLAIM**

The ornamental design for a capacitor, substantially as shown and described.

DESCRIPTION

FIG. 1 is a perspective view of a capacitor;
 FIG. 2 is a front view thereof;
 FIG. 3 is a back view thereof;
 FIG. 4 is a right side view thereof;
 FIG. 5 is a left side view thereof; and
 FIG. 6 is a top view thereof; and
 FIG. 7 is a bottom view thereof.
